UNITED STATES PATENT OFFICE.

FREDERICK OTT, OF NORRISTOWN, PENNSYLVANIA, ASSIGNOR, BY MESNE ASSIGNMENTS, TO A. T. BAKER & COMPANY, INC., OF MANAYUNK, PENNSYLVANIA, A CORPORATION OF PENNSYLVANIA.

FILE FABRIC.

1,379,931.

Specification of Letters Patent. Patented May 31, 1921.

Application filed April 11, 1919. Serial No. 289,290.

To all whom it may concern:

Be it known that I, FREDERICK OTT, a citizen of the United States, residing at Norristown, county of Montgomery, and 5 State of Pennsylvania, have invented a new and useful Improvement in Pile Fabrics, of which the following is a full, clear, and exact description, reference being had to the accompanying drawings, which form a part 10 of this specification.

My invention relates to cut pile fabrics wherein two backing fabrics, connected by pile warps extending continuously through both fabrics and from one to the other, are 15 cut in a plane midway between and parallel to both backing fabrics to form two halves, each constituting a complete finished fabric having on one face a multitude of short upright cut pile ends. 20 The fabric displays characteristics common to woven pile fabrics in that it is composed of a top backing, a bottom backing, pile warp threads which interlace with the weft or filler threads of both backings and 25 also extend between the top and bottom fabrics, and binder warp threads each of which extends through only a single backing. The fabric is conveniently woven on a double loom, two filler shots or weft picks 30 being thrown simultaneously.

The fabric also displays features which are not common to woven pile fabrics having the characteristics specified. In appearance, it exhibits a tufted face which is 35 smooth and uniform, without the effect of twilling and without parallel ridges or grooves. In many pile fabrics, these ridges or grooves are readily noticeable, presenting often the appearance, in certain lights, of 40 parallel lines extending across the face of the fabric. The twill effect is observable even in many pile fabrics which are devoid of the ridges or grooves or parallel line effect and indeed is very apt to develop in 45 any weave which is devised to eliminate the other objectionable appearances. Another valuable characteristic of my new fabric is that localized severe pressure or friction will not permanently mar the fabric, the 50 interlacing of the yarn being such as to tend to restore displaced or flattened pile threads to normal position.

The fabric involves not only a particular

arrangement of pile warp threads but a particular arrangement of binder warp threads, 55 whereby each pile thread is securely held in proper relation to the filling threads with which it engages and to the adjacent pile threads.

The invention will be better understood 60 by reference to the accompanying drawings, in which—

Figure 1 represents a series of longitudinal sections through the fabric, the same being taken along the four pile warp threads 65 respectively.

Fig. 2 is a longitudinal section through the fabric showing the warp threads of one set, the ground warp threads or binder warp threads being indicated by single lines to 70 differentiate from the double lines by which the pile threads are indicated.

Fig. 3 is a view, similar to Fig. 2, of the pile warp threads of the second set.

Fig. 4 is a plan view of one of the backings, the same being a section through the fabric of Figs. 2 and 3 looking in the direction of the arrows.

The space between the threads relatively to the size of the threads is greatly exaggerated in order that the construction may 80 be more readily understood.

In every repeat of the fabric there are two pairs of pile warp threads 1, 2 and 3, 4. Associated with one pair of pile warp 85 threads is a set of four binder warp threads comprising a pair of binders *s*, *t*, engaging the filling of the top backing and a pair of binders *u*, *v*, engaging the filling of the bottom backing. Associated with the other 90 pair of pile warp threads is a set of four binding warp threads comprising a pair of binders *w*, *x* engaging the filling of the top backing and a pair of binders *y*, *z*, engaging the filling of the bottom backing. The 95 filling or warp threads are designated *a* to *p*, etc.

Each pile thread extends successively over, under and over three successive weft threads of one backing fabric, thence to the 100 other backing and successively over, under and over three successive weft threads thereof, and thence across to the first backing and so on. This is a known weave, but in my specific adaptation thereof the two adjacent 105 pile warp threads of each pair are arranged

to work exactly oppositely so that they intersect between the backings, the two pile warp threads of a pair never, therefore, interlocking with the same weft thread, but interlocking with corresponding weft threads of the two backings respectively. The two pile threads of one pair extend in the same direction as the respective pile threads of the adjacent pair of the same set, but one

5 10 pick in advance thereof.

Thus, pile warp thread 2 extends successively outside weft thread *a*, inside weft thread *b* and outside weft thread *c* of the top backing, thence across to the bottom 15 backing, thence successively outside weft thread *l*, inside weft thread *m* and outside weft thread *n*, and thence across to the top backing. Pile thread 1 of the same pair extends successively outside weft thread *i*, inside weft thread *j* and outside weft thread *k* of the bottom backing, thence across to the top 20 backing, thence successively outside weft thread *d*, inside weft thread *e* and outside weft thread *f*, and thence across to the bottom 25 backing. The two pile warp threads 1 and 2 intersect between weft threads *c*, *k* and *d*, *l*.

In the other pair of pile warp threads of the series, the pile warp thread 3 interlocks 30 with weft threads *b*, *c* and *d* of the top backing and *m*, *n* and *o* of the bottom backing, while pile warp thread 4 interlocks with weft threads *j*, *k* and *l* of the bottom 35 backing and weft threads *e*, *f* and *g* of the top backing, the two pile warp threads intersecting between weft thread *d*, *l* and *e*, *m*, being therefore one pick in advance of *m*, being therefore one pick in advance of (or behind, dependent upon the order in which the shots of weft are thrown) the 40 pile warp threads 1 and 2.

In weaving the goods, each pair of pile warp threads occupies one dent or split of the reed and the four associated binder warp threads are drawn in through the same 45 dent or split. The manner of interlacing of the binder threads with the weft threads is of importance. Taking the two binder warp threads *s*, *t*, of the top backing associated with the two pile warp threads 1 and 2: 50 Binder *s* floats on the outside of weft threads *a*, *b* and *c*, thence extends successively inside weft thread *d*, outside weft thread *e* and inside weft thread *f*, thence floats outside the next three weft threads, binds in the 55 three weft threads following and so on. Binder *t* extends successively inside weft thread *a*, outside weft thread *b* and inside weft thread *c*, thence floats outside weft threads *d*, *e* and *f*, binds in the next three 60 weft threads, and so on. It will thus be seen that one binder, *s*, always binds in the pile warp thread 1 and floats outside the filling where the pile warp thread 1 interlaces with the bottom backing, and that the other com- 65 panion binder *t* always binds in the pile

warp thread 2 and floats outside the filling where the pile warp thread 2 interlaces with the bottom backing.

The other two binder warp threads *u*, *v*, of the same set are similarly interlaced with the filling of the bottom backing, and the binder *u* always binds in the pile warp thread 1 and the binder *v* always binds in the pile warp thread 2.

Binder threads *w*, *x*, *y* and *z* occupy a similar relation to pile threads 3 and 4.

It will be observed that both binder warp of a set (for example, threads *s* and *t*, Fig. 2) extends over or outside each weft thread (for example, thread *e*) under or within which the adjacent pile warp thread (thread 1) extends. This feature is of importance in that the pile thread, at such point in the knitting, does not pass from one backing to another, but passes to the center of the fabric and back again and hence is relatively slack. In the event of any irregularity as, for instance, a knot or lump, in the yarn at this point, the pile thread, if it slides along a binder warp thread, may not pull through and produces an irregularity in the goods at this point. In my improved weave, however, both binder warp threads of a set are on the outside of the fabric at this point and thus afford no obstruction to the free slippage of the yarn.

Having now fully described my invention, what I claim and desire to protect by Letters Patent is:

1. A pile fabric composed of two backings 100 fabrics comprising weft threads and pile warp threads all interwoven with the weft threads of both backings, the pile threads being arranged in pairs, the threads of each pair crossing between the backings and extending in opposite directions backward, forward and backward around successive weft threads in each backing, the threads of one of said pairs being one pick in advance of the threads of the adjacent pair; 110 and four binder warp threads associated with each pair of pile warp threads, of which two are in each backing, each of the said two binder warp threads of a set extending successively forward, backward and 115 forward around three successive weft threads while its companion thread floats over the back of the same three weft threads, each of said binder threads, where it extends successively forward, backward and 120 forward around three successive weft threads lying adjacent to a pile warp thread which extends successively backward, forward and backward over the same three successive weft threads.

2. A pile fabric composed of two backings 125 fabrics comprising weft threads and pile warp threads all interwoven with the weft threads of both backings, the pile threads being arranged in sets of two pairs each, the 130

threads of each pair crossing between the backings and extending in opposite directions backward, forward and backward around successive weft threads in each 5 backing, the threads of one of said pairs being one pick in advance of the threads of the other pair respectively; and four binder warp threads associated with each pair of pile warp threads, of which two are 10 in each backing, each of the said two binder warp threads of a set extending successively forward, backward and forward around three successive weft threads while its companion thread floats over the back of the 15 same three weft threads, both of said two binder warp threads of a set being arranged to extend to the back of a weft thread where the adjacent pile thread extends to the front of the said weft thread.

20 3. A cut pile fabric comprising weft threads, pairs of binder warp threads, and two sets of cut pile warp threads between each pair of binder warp threads; each pile warp thread passes from front to back, then 25 to the front, then to the back, and then to the front about three successive weft threads, the one set of pile warp threads being staggered with relation to the other set, the arrangement being such that each thread 30 of a set passes about three successive wefts while the threads of the other set pass about the next three wefts successively, the one binder warp of each set passes successively from back to front around three successive 35 warp threads and then floats over the back of the next three wefts, while the other binder warp of said set passes from back to

front around the three successive weft threads over which the other weft thread of said set floats, and floats over the back of 40 the next three weft threads around which the companion binder warp thread passes, the floating portions of each binder warp lie adjacent to a cut pile warp thread which is interwoven with the weft threads together 45 with the adjacent portions of the companion binder warp thread.

4. A cut pile fabric comprising weft threads, pairs of binder warp threads, and two sets of cut warp threads out of longitudinal alinement, between each pair of binder warp threads, each pile warp thread passes from the front about successive weft threads and back to the front, the threads of one set of pile warp threads being staggered with 50 relation to the threads of the other set, portions of each binder adjacent to the pile warp threads floating over the back of the weft threads which are interwoven with the pile warp threads, while the adjacent portions of the companion binder warp threads are interwoven with the weft threads and the pile warp, the arrangement being such that the binder warp threads will not pass around the weft threads with an adjacent 55 pile warp thread.

In testimony of which invention, I have hereunto set my hand, at Philadelphia, Pa., on this 31st day of March, 1919.

FREDERICK OTT.
